LOADING AND TRANSPORTING DEVICE

Ben Phillips and Merle Phillips, Planada, Calif.

Application February 28, 1947, Serial No. 731,602

2 Claims. (Cl. 214—65)

1

The present invention relates to an improved loading device and it consists in the combinations, constructions and arrangements of parts herein described and claimed.

The invention contemplates the provision of a machine for transporting stacks of trays and then, at the will of the operator, transferring them to the ground one at a time. It also contemplates the provision of mechanical means for picking up trays one at a time and transporting the completed stack from one place to another.

It is accordingly an object of the invention to provide an improved means whereby the lower-most tray of a stack of trays carried in an apparatus may be mechanically removed therefrom.

It is a further object of the invention to provide means whereby a tray may be mechanically removed from the ground and placed upon the bottom of a stack of trays.

A further object of the invention is the provision of novel mechanical movements for accomplishing the aforementioned objects.

Other and further objects of the invention will become apparent from a reading of the following specification taken in conjunction with the drawings, in which:

Figure 1 is a front elevational view of an apparatus embodying the invention.

Figure 2 is a side elevational view thereof.

Figures 3 to 6, inclusive, are fragmentary views illustrating the operation of a certain phase of the invention, and

Figure 7 is a fragmentary plan view illustrating certain details of the invention.

Referring more particularly to the drawings, there is shown therein an embodiment of the invention comprising a framework having a lower base portion 10 of generally rectangular shape a plurality of uprights 11 attached thereto and an upper base portion 12 carried by the uprights 11. Upon the upper base portion 12 is mounted a source of power 13, preferably an internal combustion engine, provided with a horizontally extending shaft 14, the outer extremity of which is provided with a bevel gear 15 which is enmeshed with a bevel gear 16 carried at the upper end of a transmission shaft 17 which is adapted to transmit power to wheels 18 through a universal 19 and axles 20. A gear shifting device 21 is also provided on the upper base 12 and has the customary gear shift lever 22.

Horizontally extending from the upper end of the source of power 13 is a shaft 23 adapted to be driven by the motor 13. The shaft 23 is connected into a gear shifting device 24 provided

with the customary shifting lever 25 and a driven shaft 26 protrudes from the free end of the gear shifting device. The driven shaft 26 terminates in a pair of sprockets 27 and 28 over which are trained, respectively, drive chains 29 and 30. The chain 29 is trained over a sprocket 31 carried by one end of a crank shaft 32 revolvably mounted horizontally in the side of the framework and the chain 30 is trained over a like sprocket 33 carried by a like crank shaft mounted in the other side of the framework.

The framework carries a pair of dirigible wheels 34 at the opposite end of the framework from wheels 18. Pick-up arms are provided and consist of a relatively long vertical inner member 40, a relatively short vertical outer member 41, a horizontally extending member 42, a diagonally extending member 43 interconnecting the lower end of the outer member 41 and points adjacent the bottom of the inner member 40 and a diagonally extending member 44 interconnecting the juncture between members 41 and 43 and the upper inner juncture of the members 40 and 42. Adjacent the upper and outer corner of the pick-up arm structure is provided a bearing 45 which surrounds a crank 46 carried by crank arms 47 in the shaft 32. The lower ends of the pick-up arms are provided with inwardly extending feet 48. Adjacent the inner sides of the uprights 11 at either end of the shaft 32 is mounted a cam 49 which is adapted, in each case, to bear against a roller 50 carried by the framework immediately below the cam. The shaft 32 is revolvably mounted in the uprights 11 in slots 51 which will allow for vertical movement of the shaft against the action of a spring 52 interconnecting the shaft and a horizontally extending cross bar 53 attached to the uprights 11 at the lower end of the framework. It will be understood that the crank shaft upon the other side of the framework is similarly constructed, similarly mounted and similarly provided with pick-up arms and a spring. Steering handles 54 and 55 are provided with vertical extensions of the rearmost uprights 11. A cam 56 is carried by the shaft 32 and is adapted to actuate a lever 57 which is pivotally mounted as indicated at 58 and has its upper end 59 attached to suitable linkage 60, 61 and 62 whereby vertically extending arms 63 and 64 are moved inwardly and outwardly. The arms 63 and 64 are each provided with a series of tray retaining fingers 65 and 66, respectively.

In operation it will be apparent that the operator of the apparatus will first start the motor

13 and then through lever 22 causing power to be transmitted to the wheels 18. Steering is accomplished by placing his hands upon the handles 54 and 55, the wheels 34 responding to the operator's pressure thereupon when it is desired to stop it is only necessary to place the gear lever 22 in neutral position. If it is desired to deposit a tray from a stack carried within the apparatus by means of the fingers 65 and 66 the lever 25 is moved to the proper position and held there for a sufficient length of time until through shaft 26 and chains 29 and 30 sufficient movement has been imparted to the shafts 32 (and like shaft upon the other side of the apparatus) to cause an entire revolution of said shafts. This will cause the upper ends of the pick-up arms to be revolved by the cranks 46. However, since the cams 49 ride upon the rollers 50, the feet 48 will remain in a relatively stationary position with respect to the ground while being withdrawn horizontally from beneath the trays due to the fact that during a portion of the lifting of the pick-up arms with respect to the shaft 32, the shaft itself is being moved downwardly by the action of the spring 52 and the depressions in the cams 49. Upon further revolution of the shaft 32 the pick-up arms will be lifted vertically with respect to the ground and again have their feet 48 returned to a position beneath the next upper tray. A study of Figures 3 to 6, inclusive, will illustrate these movements. While this is occurring, through the action of cam 56 and the levers and linkage 57, 59, 60, 61 and 62 the fingers 65 and 66 will have been withdrawn and again replaced between the separate trays.

While but one form of the invention has been shown and described herein, it will be readily apparent to those skilled in the art that many minor modifications may be made without departing from the spirit of the invention or the scope of the appended claims.

What is claimed is:

1. An apparatus of the character described comprising a frame, drive wheels and dirigible wheels mounted upon the frame, means carried by the frame for carrying a plurality of trays, means carried on the frame for selectively picking up and depositing a single tray with relation to the ground, said means including crankshafts carried by the frame, cranks upon the crankshafts, pick-up arms having tray engaging feet carried by the cranks, means for retaining said feet at a constant distance from the ground while engaging and disengaging the feet with the trays, means for individually supporting

trays stacked in the apparatus while the feet are engaging and disengaging with the single tray, means for releasing said last-mentioned means when said single tray is moved vertically, 5 a source of power carried on the frame and suitable transmissions and gear shifting mechanisms for transferring power to the drive wheels and the pick-up and deposit and supporting means. 2. An apparatus of the character described 10 comprising a frame, drive wheels and dirigible wheels mounted upon the frame, means carried by the frame for carrying a plurality of trays, means carried on the frame for selectively picking up and depositing a single tray with relation to the ground, said means including crankshafts carried by the frame, cranks upon the crankshafts, pick-up arms having tray engaging feet carried by the cranks, means for retaining said feet at a constant distance from the ground 15 while engaging and disengaging the feet with the trays, means for individually supporting trays stacked in the apparatus while the feet are engaging and disengaging with the single tray, means for releasing said last-mentioned means when said single tray is moved vertically, a source of power carried on the frame and suitable transmissions and gear shifting mechanisms for transferring power to the drive wheels and the pick-up and deposit and supporting means, 20 said means for individually supporting the stacked trays including a pair of vertically extending arms carried by the frame at either inner side thereof, a plurality of spaced inwardly directed tray-engaging fingers on each of said arms 25 and means for horizontally moving said arms whereby said fingers engage and disengage the stacked trays.
